UNITED STATES PATENT OFFICE.

SAMUEL EVERETT DOANE, OF CLEVELAND, OHIO, ASSIGNOR TO THE NATIONAL ELECTRIC LAMP COMPANY, OF CLEVELAND, OHIO, A CORPORATION OF NEW JERSEY.

INCANDESCENT LAMP.

SPECIFICATION forming part of Letters Patent No. 762,030, dated June 7, 1904.

Application filed December 12, 1903. Serial No. 184,914. (No model.)

To all whom it may concern:

Be it known that I, SAMUEL EVERETT DOANE, a citizen of the United States, residing at Cleveland, in the county of Cuyahoga and State of Ohio, have invented a certain new and useful Improvement in Incandescent Lamps, of which the following is a full, clear, and exact description, reference being had to the accompanying drawings.

It is at present the almost universal practice to employ solid platinum wire for the lead-in wires of incandescent lamps. Platinum has two desirable qualities for lead-in wires not possessed conjointly by any other metal in any satisfactory degree—viz., it is not oxidizable and its coefficient of expansion is substantially the same as that of glass. It is because it has these qualities that the expensive practice of using platinum wire for the purpose specified is continued.

The object of the present invention is to permit the use of less expensive wire as the lead-in wires of such lamps.

There are metals—as, for example, certain aluminium-iron alloys—whose coefficient of expansion is substantially the same as that of certain glass which may be used in making lamp-stems. It has not heretofore been possible to use such wire, however, because it oxidizes easily, even when embedded in the glass. When it does oxidize, air will leak in between the glass and the oxidized surface of the wire into the bulb, and thus destroy the vacuum therein. I have discovered, however, that if one coats such a wire, as by electroplating, with a thin skin or shell of non-oxidizable metal, as gold, and then seals one or both ends of the short sections of said wire by fusion such sections may be successfully used as the lead-in

wires of incandescent lamps and analogous structures. In that case the metal core cannot be oxidized after being so coated and sealed, or if it were oxidized air could not, because of the seal, get between the oxidized surface of the core and the non-oxidizable coating. Sometimes the core metal in being drawn into wire is not perfectly cylindrical, but, on the contrary, has a crease or fold running longi-

tudinally, as shown in Fig. 3. If such a wire were electroplated with gold, for example, and its ends were not sealed, air could leak between the gold coating and the core through this longitudinal crease; but if the ends of such wire are sealed by fusion such leakage cannot take place. Another kind of coated wire may also be used—to wit, a drawn wire having a metal core and a platinum shell. Such wire is to be obtained in the open market, and the platinum shell is so thick, comparatively, that it controls the expansion and contraction of the wire. By fusing, and thereby sealing one or both ends of short sections of this wire, leakage of air between the shell and core is prevented and such short sections may be used as the lead-in wires.

My invention therefore is adapted for use with coated wires of either type referred to; and it consists in the employment as the lead-in wires of incandescent lamps and analogous devices of wire having a metallic core and a non-oxidizable coating and having one or both of its ends sealed by fusion. It also consists of an incandescent lamp in which such lead-in wires are employed, and also in the more specific details of construction hereinafter set forth, and definitely pointed out in the claims.

In the drawings, Figure 1 is a longitudinal sectional view of an incandescent lamp embodying the present invention. Fig. 2 is an enlarged sectional view of a portion of the glass end of the lamp-stem, in which glass end is embedded the joint between a conductor-wire and a coated lead-in wire having its ends sealed by fusion. Fig. 3 is a very much enlarged section of a wire having a creased core and an outer coating of non-oxidizable metal electroplated thereon.

A represents the lamp-bulb, and B the glass stem thereof.

C C represent the conductor-wires, which are usually made of copper, and D the coated lead-in wires. The coating thereof is not oxidizable. In preparing these lead-in wires for use proper lengths thereof are severed from the spool, preferably by electrically fusing them off. By this method of procedure the

ends of the severed sections are melted and then when cool they close the ends of the tubular platinum shell and effectually prevent any access of air between it and the metal core. It is of course apparent that these lead-in wires may be cut off and then their ends may be fused electrically on a blowpipe-flame, thereby attaining the same desirable result. There is, however, a distinct advantage in severing them electrically, as stated, because it is substantially as cheap a method of procedure as it is to cut them off, and thereby both ends of the short lead-in wires are effectually sealed. This is a desirable precautionary condition and is attained without any additional expense. If by chance one end were not perfectly sealed by the fusion and the other end were, access of air to the bulb between the coating and core of a lead-in wire will be prevented. In using these coated lead-in wires having their ends sealed as stated the conductor-wires may be connected thereto in the usual manner or any suitable manner, as by what is known in this art as "welding." The joint between the conductor-wires and lead-in wires and short adjacent portions of said wires are then embedded in the glass of the end of the stem in the usual manner. It is

obvious that this manner of providing for electrical connections between the interior of a vacuum-tube and the exterior thereof may be employed in connection with various devices analogous to incandescent lamps.

Having described my invention, I claim—

1. In an electric lamp, a lead-in wire having a metallic core and a non-oxidizable metallic coating, one end of said wire being sealed by fusion.

2. In an electric lamp, a lead-in wire having a metallic core and a non-oxidizable metallic coating, both ends of said wire being sealed by fusion.

3. In an electric lamp, a lead-in wire having a metallic core and a non-oxidizable metallic coating, the outer end of said wire being sealed by fusion, combined with a conductor-wire fastened to said lead-in wire, and the lamp-stem, in the closed glass end of which the joint between said wires is embedded.

In testimony whereof I hereunto affix my signature in the presence of two witnesses.

SAMUEL EVERETT DOANE.
